DESIGN FOR A DRESS

Sylvia Comolli, New York, N. Y.

Application November 27, 1937, Serial No. 73,232

Term of patent 3½ years

To all whom it may concern:

Be it known that I, Sylvia Comolli, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The characteristic feature of my design resides in the specific trim on the dress, as shown.

I claim:

The ornamental design for a dress, substantially as shown, and described.

SYLVIA COMOLLI.
